TOWEL HANGER

Gladys B. La Mere, 2363 Chestnut St.,
San Francisco, Calif.

Filed Oct. 26, 1961, Ser. No. 67,271

Term of patent 14 years

(Cl. D4—3)

I claim:

The ornamental design for a towel hanger, as shown.
